United States Patent Office.

ALFRED F. SUMMERS, OF PEORIA, ILLINOIS, ASSIGNOR TO HIMSELF,
CHAUNCEY NYE, AND THOMAS A. SLACK.

Letters Patent No. 81,555, dated August 25, 1868.

IMPROVED POST-HOLE BORER.

The Schedule referred to in these Letters Patent and making part of the same.

Be it known that I, ALFRED F. SUMMERS, of the city of Peoria, in the county of Peoria, and State of Illinois, have invented a new and useful Machine for Boring Post-Holes; and I do hereby declare that the following is a full, clear, and exact description of the construction and operation of the same, reference being had to the annexed drawings, making part of this specification, in which—

Figure 1 is a perspective view.

Figure 2 is a plan.

Figure 3 is a longitudinal elevation.

Figure 4 is a section of the boring-apparatus on a larger scale.

Figure 5 is a view of the cutting-part of the auger.

Figure 6 is a view of the convex surface of the dirt-remover.

Figure 7 is a view of the auger at work, and

Figure 8 is a view of the collar of the dirt-remover.

My invention consists in the construction of a post-hole machine, moving upon wheels, so arranged that distance may be measured by the machine as it passes over the ground, and by means of which the screw is applied to the working of the boring-apparatus.

To enable others skilled in the art to make and use my invention, I will proceed to describe its construction and operation.

I construct a platform or body of the carriage *A a a*, in the form of an isosceles triangle, with an opening in the same, of sufficient length and breadth to afford room for the movements of the boring-apparatus.

I support the body by three wheels, one of which is a measuring-wheel, *H*, placed near the vertex of the triangle, as represented in fig. 1, and the other two arranged upon a revolving axle, in a manner similar to railroad-car wheels, and attached near the base of the triangle.

Over the opening in the body of the carriage *A a a*, I place an adjusting-slide, *B B*, provided also with an opening in the middle of the same, of the requisite form and size to afford sufficient play to the auger *E* and dirt-remover *G u u f*, and hold the same down to the body, by means of the metallic plates *I* and *J*, which are firmly bolted to the cross-pieces of the body of the carriage. The standards *b b b*, attached to the slide *B B*, support the boring-apparatus, and by this combination and arrangement, the auger may be moved from side to side of the body of the carriage, and worked at any point between the sides.

C is a universal axle, consisting of two axles placed at right angles, and containing a spherical concave nut, through which the screw *D* works, and by means of which the auger is kept constantly in a perpendicular position by its own weight.

D is a screw, of requisite size, and *d* is a wheel upon the head of the screw, having upon the circumference a handle, by which the screw is turned.

The shaft of the auger *E* is connected with the screw *D* by the swivel-joint *e*, as represented in fig. 4. This joint consists of two sections, of which the upper section is a concave nut, used upon the lower end of the screw, and the lower section is a hollow cylinder, having the hollow of the same of less diameter than that of the screw.

Upon the upper end of the shaft of the auger *E*, and within the swivel-joint *e*, is a round head or nut, of a diameter equal to that of the screw *D*, which forms the connection of the shaft *E* to the swivel-joint *e*.

In the lower end of the swivel-joint is a notch, produced by extending the same downward, (*g*, figs. 3 and 4,) in such a manner that it resembles a single wind of the thread of a screw cut off at the point where the circle becomes complete.

h is a hole in the side of the swivel, by means of which the swivel is lubricated.

g is a pin or stop, firmly fixed in the shaft of the auger *E*, at such a distance below the head of the shaft that it falls below the notch in the lower end of the swivel-joint, when the auger is relieved from the pressure of the screw.

F is the worm or cutting-part of the auger.

I attach to the auger and screw a dirt-remover, consisting of the convex plate G, having a round hole through the centre, of a diameter a little larger than that of the auger, and held in position by the rods u u, which connect the same with the collar f.

f is also a concave nut, which runs upon the screw D, between the universal axle C and the swivel-joint e.

The measuring-wheel H is made of such size that its circumference may be conveniently divided into equal spaces or arcs by the pins i, j, k, l, m, n, o, and p, and it is also divided in the same manner by radii, or lines extending from the centre of the wheel to the pins i, j, k, l, m, n, o, and p, and numbered respectively 1, 2, 3, 4, 5, 6, 7, and 8. This wheel is also provided with ridges or projections upon the tire, to prevent the same from slipping upon the ground.

q is a flat, pointed piece of metal, riveted to the plate J, in such a position that the pins i, j, k, l, m, n, o, and p touch and spring the same as the wheel H revolves, indicating, by the number of clicks produced, the distance passed over by the carriage.

r s is a brake, so adjusted that it may be applied to the measuring-wheel H, to prevent the same from revolving.

Operation.

Figure 1 represents the machine in position for boring.

The screw D is driven down by turning the wheel d. The descent of the screw drives the swivel-joint down upon the shaft of the auger E, as the cutting-part of the auger F comes in contact with the ground, and the pin or stop g catches in the lower end of the swivel-joint, and turns the auger. The auger is then driven down to the depth required.

On reversing the movement of the wheel d, the auger is drawn out; and, as the screw is drawn up, the pin g falls below the notch in the lower end of the swivel-joint e. The joint then acts as a swivel, and the auger is drawn up steadily and without turning, thereby saving the dirt from falling or winding back into the hole, from or through the worm or cutting-part of the auger. As the pulverized dirt is forced up through the hole in the convex plate G, by the elevation of the auger, it slides away from the shaft of the auger, down the declining surface of the convex plate G, and, as the whole boring-apparatus is finally raised from the ground by the working of the screw, whatever dirt then remains upon the plate slides off, and drops from the rim of the plate far enough from the hole to be prevented from falling into the same.

The measurement of distance by the measuring-wheel H is effected as follows: As the wheel revolves, the distance is indicated by the clicks produced by the striking of the pins i j k, &c., against the spring g, and also by the position of the radii or lines numbered 1 2 3, &c., which may be determined by the eye.

By means of the combination of the adjusting-slide B B and the standards b b b, any deviation from a right line may be corrected by moving the slide to the right or left upon the body of the carriage without moving the carriage itself.

Claims.

Having thus fully described my invention, what I claim therein as new, and desire to secure by Letters Patent, is—

1. The adjusting-slide B B, and the standards b b b, the universal axle C, containing the spherical nut, the screw D, the swivel-joint e, and the measuring-wheel H, as described, arranged, and operated, in combination with a carriage and auger, substantially in the manner and for the purposes as herein set forth.
2. The auger E F, and adjustable concave plate G, in combination with the swivel-joint e and screw D, as described, and operating substantially in the manner and for the purposes set forth.
3. The carriage A a a, as described, in combination with the auger E F and its operating-devices, substantially in the manner and for the purpose set forth.

ALFRED F. SUMMERS.
